*H. A. Landry,
Railroad Chair*

N° 22,656.

Patented Jan. 18, 1859.

Fig. 4.

UNITED STATES PATENT OFFICE.

HENRY A. LANDRY, OF CAMDEN, NEW JERSEY, ASSIGNOR TO A. B. STOUGHTON, ASSIGNOR TO F. G. RANSFORD, OF TROY, NEW YORK.

RAILROAD-CHAIR.

Specification of Letters Patent No. 22,656, dated January 18, 1859.

To all whom it may concern:

Be it known that I, HENRY A. LANDRY, of Camden, in the county of Camden and State of New Jersey, have invented a new and useful Improvement on Railroad-Chairs; and I do hereby declare that the following is a full, clear, and exact description of the construction and operation of the same, reference being had to the annexed 10 drawings, making part of this specification, in which—

Figure 1, is a perspective view. Fig. 2, is a sectional side view. Fig. 3, is a perspective view of the chair, showing a perspective view of the rails in their place and set in cross tie. Fig. 4 is a section view of the chair, showing the end of a rail, and chair bedded in cross tie, and both rail and chair carrying the cone of a wheel, as 20 in actual operation.

Letter *a*, in Figs. 1 and 2, represents the projecting piece of metal which is cast on and chilled so as to harden the running surface which projection may also be made of 25 wrought iron or steel and secured to the chair or rails themselves.

Letter *b*, Figs. 1 and 2, represents the support or jams afforded to the rails in their lateral pressure.

Letter *c*, Figs. 1 and 2, shows the seat for the rail which rail is wedged up tight into its place against the jam *b*, Figs. 1 and 2, by means of the spikes passed through the holes *g*, *g*, Figs. 1, 2.

Letter *e*, Fig. 2, shows the inner side of the projecting piece of iron, which is kept as close to the rail as possible but not so close as to prevent the rail being wedged tightly up into its place by means of the 40 spikes passing through the holes *g*, *g*.

Letter *d*, Fig. 2 shows the manner in which I propose to strengthen the back of the chair, so as to prevent fracture, when the weight of the passing machinery is 45 thrown on the top of the projecting piece at *a*, Fig. 2.

Letters *h*, *h*, Figs. 1 and 2, are merely holes for securing the chair in its place on the cross tie.

Letters *j*, *j*, Fig. 3, show the ends of two rails which ought to be kept as close as possible, but when laid in cold weather a space,

letter *K*, Fig. 3, is obliged to be allowed for their expansion in warm weather, which space *K*, Fig. 3, is to be supported by the 55 projecting piece as shown at *a*, Fig. 3. The projecting piece *a*, Fig. 3, is level with the rails at its two extremities as marked by the letters *n*, *n*, but raised a trifle higher in the center where the ends of the rails meet 60 at *j*, *j*, Fig. 3 or where the space *K* Fig. 3, occurs so as to take the weight off the extremities of the rails.

The letters *o*, *o*, Fig. 3, show where two small but oblong gains are made in the rails, 65 and partly made to cover the holes of chairs at *g*, *g*, Fig. 3, so that the spikes may push the rails firmly into their seats and bring the rails against the jam *b*, Fig. 4, and as close as possible against the projecting piece 70 *a*, Fig. 3.

The letters *h*, *h*, Fig. 3, are the spike holes through which the chair is secured to the cross tie *m*, *m*, Fig. 3.

In Fig. 4, *f*, is the rail laid in its seat *c*, 75 and pressed tightly into its seat and made to bear against the jam *b*, by means of the spike passing through *g*.

The letter *e*, Fig. 4 shows the inner face of the projecting piece *a*, Fig. 4 in close 80 contact with *f*, Fig. 4, in consequence of the lateral pressure of the wheel *r*, Fig. 4, at the same time the cone of the wheel *r*, Fig. 4 is partially bearing on the surface of the rail *f*, and top of the projecting piece *a*, Fig. 4, 85 the entire chair being let into the cross tie about $\frac{3}{4}$ of an inch is firmly secured in its place by the spikes *g*, and *h*, Fig. 4, which pass through the chair and are driven into the cross tie *m*, Fig. 4.

By this chair I propose to afford a bearing to the cones of the wheels of locomotives and cars of rail roads thereby preventing the unpleasant jarring of the machinery and the undue wearing of that particular part of the rails of a rail road; these chairs may be made of any required size and strength taking as much bearing from the ends of the rails as persons making them may choose to afford and can also be made 100 to suit any of the rails known or used.

What I claim as my invention and wish to secure by Letters Patent, is—

The improvement of a projecting piece of

metal either cast on the rail road chair or made of wrought iron or steel and affixed, and rising up along side of the rails on rail roads where two rails meet, and of sufficient height to receive all or a part of the weight of the machinery, while passing over that particular part of the rails as herein de-

scribed, disclaiming any right to any particular form or pattern of chair to which my improvement may be applied.

HENRY A. LANDRY.

In presence of—

CHARLES D. FREEMAN,

Wm. C. GAUW.
